(57) **CLAIM**

The ornamental design for a handrail ladder, as shown and described.

DESCRIPTION

FIG. 1 is a front elevation view of a handrail ladder showing the new design in a folded state;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a front elevation view of the handrail ladder in a first unfolded state;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a first perspective view thereof;

FIG. 16 is a second perspective view thereof; and,

FIG. 17 is a perspective view of the handrail ladder in a second unfolded state.
